UNITED STATES PATENT OFFICE.

EDGAR H. MUMFORD, OF PHILADELPHIA, PENNSYLVANIA.

MECHANISM FOR DRAWING PATTERNS.

1,075,117.

Specification of Letters Patent.

Patented Oct. 7, 1913.

Application filed April 23, 1910. Serial No. 557,108.

To all whom it may concern:

Be it known that I, EDGAR H. MUMFORD, a citizen of the United States, residing at Philadelphia, in the county of Philadelphia and State of Pennsylvania, have invented 5 certain new and useful Improvements in Mechanism for Drawing Patterns, of which the following is a specification.

My invention has reference to mechanisms 10 for drawing patterns from sand molds, and it has for its primary objects; the provision of an improved mechanism for drawing patterns whereby the pattern is held steady during the drawing; the provision of improved mechanism wherein the pattern is 15 held steady by brace means supported from the drawing mechanism; and the provision of a simple and inexpensive drawing rig which will effectively hold the pattern 20 against tilting movement during the drawing operation. These and such other objects as may hereinafter appear, or are incidental to my invention, I attain by means 25 of a device illustrated in preferred form in the accompanying drawings, wherein,

Figure 1 is a side elevation of a drawing mechanism embodying my invention, and

Figure 2 is a side elevation of a slightly modified form of my invention.

Referring to the drawings, it will be seen 30 that I have shown my improved drawing mechanism applied to a pattern plate 5, of usual construction, which is provided with a guide means 6 of any desired type. My 35 invention is designed to steady the pattern plate during the drawing operation, and to this end I provide a drawing member 7, preferably composed of a head 7' and a chain or other member 8, preferably flexible, 40 which is provided with a hook 9 for attachment to a pattern lifting screw or other suitable connection 10. Pivoted to the head 7' are three legs or rods, 11, 12 and 13, which have their ends resting on the pattern 45 plate pointed. This arrangement constitutes in effect a tripod brace or steady member, and when the slack of the chain 8 is being taken up, the pivoted legs of the tripod will drag over the pattern plate, and 50 position themselves thereon when the chain or drawing member is taut, the pointed ends of the legs biting into the pattern plate. It will be seen that there is thereby provided an effective steady means for the pattern 55 during the drawing operation, inasmuch as there can be no tilting movement of

the pattern plate, follow board or pattern extension, to any of which the pattern may be attached for the ramming of the mold.

In Figure 2, I have shown the tripod 60 brace mechanism slidably mounted on a rod 13, which is provided with an eye at each end to receive the crane or hoist hook, and the chain 8. In this arrangement the legs of the tripod are preferably positioned 65 in caps or sockets in the pattern plate in the manner indicated, the stress of drawing being taken by the rod 13. It is, of course, to be understood that this construction, if desirable, may be used in the same manner 70 as that of Figure 1.

My construction is simple and inexpensive and provides an effective means for holding the pattern plate, and thereby the pattern, steady during the drawing, and it is 75 obvious that the legs of the tripod brace can readily be adjusted and positioned according to the character of the work to be done, and with improved results. My device is designed for use on pattern plates, 80 or the equivalents thereof, namely follow boards, and pattern extensions in such cases as where the use of a pattern plate *per se* is impracticable, and it is understood that the term pattern plate used in the claims is 85 intended to cover any such means for securing the pattern, and it is likewise understood that the term flexible drawing member is intended to cover any member which performs the function of the member 8. Other 90 advantages of my construction will be apparent to those skilled in the art.

Having thus described my invention and illustrated its use, what I claim as new and desire to secure by Letters Patent is the following:

1. In a device for drawing patterns, a flexible lifting member adapted to draw the pattern, and means coöperating therewith as the flexible member becomes taut 100 for transferring the center of oscillation of such flexible member from its point of attachment to the pattern to a point higher up, whereby all of the said lifting member below such higher point becomes a part of a 105 rigid pattern carrier.

2. The combination with a pattern plate of a flexible lifting member therefor and brace means supported thereon and adapted to engage the pattern plate at a plurality of 110 points removed from the point of attachment of the lifting member.

3. A device for drawing patterns comprising a flexible member, and a plurality of brace rods arranged thereabout and pivoted near their intersection therewith, said rods engaging the pattern plate and holding it against tilting movement.

4. A device for drawing patterns comprising a flexible drawing member adapted to be attached to the pattern plate and a plurality of brace rods arranged thereabout and pivoted near their intersection there-

with, the said rods being positioned when the drawing member is taut and holding the pattern plate against tilting movement.

In testimony whereof I have hereunto ¹⁵ signed my name in the presence of the two subscribed witnesses.

EDGAR H. MUMFORD.
